UNITED STATES PATENT OFFICE.

JOSEPH FRIEDLANDER, OF NEW YORK, N. Y.

Mounting for Eyeglasses.

1,091,825.

Specification of Letters Patent. Patented Mar. 31, 1914.

Application filed March 31, 1911. Serial No. 618,108.

To all whom it may concern:

Be it known that I, JOSEPH FRIEDLANDER, a citizen of the United States, and a resident of the State, county, and city of New 5 York, borough of Manhattan, have invented new and useful Improvements in Mountings for Eyeglasses, of which the following is a specification.

This invention relates to certain improvements in eyeglasses, and more particularly to the construction of the nose clip and the means for supporting and attaching the same to the bridge, frame or other adjacent parts of the eyeglasses.

10 15 The main features hereinafter described and claimed in this application are disclosed in my prior application Serial No. 549,143, filed March 14, 1910.

One of the main objects of my invention is 20 to facilitate the adjustment of the clip, whereby the latter may be readily bent to any desired position, so as to fit the nose of the wearer.

By means of my improved construction, 25 the two clips may be brought toward or from each other, raised or lowered and moved toward or from the plane of the lenses without interfering with the normal operation of the clips in placing the eyeglasses upon or removing them from the nose.

A further important feature of my invention relates to the attachment of the nose clip to a lever in that type of eyeglasses in 30 35 which a rigid bridge is employed and to which the clips are movably secured. By means of my invention the clips may have a limited movement in respect to their corresponding levers, and the screws which hold the clips in place have a firm hold in the parts through which they extend.

Reference is to be had to the accompanying drawings, which form a part of this specification, and in which similar reference 40 45 characters indicate corresponding parts in the different views.

Figure 1 is a plan view of a blank from which I may form one embodiment of my improved lever; Fig. 2 is a perspective view 50 55 of a lever formed from the blank shown in Fig. 1; Fig. 3 is an inverted plan view of a portion of a pair of eyeglasses showing my improved lever and clip; Fig. 4 is a plan view of a slightly modified construction in which the clip is provided with two arms

for engagement with the lever; Fig. 5 is a side elevation of a portion of the construction shown in Fig. 4; Fig. 6 is a rear view of a clip constructed in accordance with my invention and of the character shown in Fig. 3; Fig. 7 is an edge elevation of the clip shown in Fig. 6; Fig. 8 is a rear view of a clip constructed for use in glasses having a spring bow and rigid clip; Fig. 9 is an edge view of the clip shown in Fig. 8 and a portion of the adjacent parts to which it is connected; and Fig. 10 is a perspective view of a clip with the plurality of leaves integral with the clip rather than integral with the lever.

My improved clip in one of the forms shown, is adapted for use with a movable lever, while in another form it is adapted for use with eyeglasses having a spring bow. In the form in which a lever is employed, my present invention does not in any way involve the means for pivotally mounting the lever or controlling its movement by spring pressure. For mounting the lever, I preferably employ the means shown in my prior application above referred to, although it is evident that any other suitable form of connection might be employed.

In Figs. 3 and 4, I have shown a part of a pair of eyeglasses in which there is a rigid bridge 12 terminating in a lens clamp 13 for holding a lens 14. Intermediate between the body of the bow and the lens clamp, a suitable pivot pin 15 serves to mount a lever, one end of which is connected to a nose clip and the other end of which constitutes a finger grip. The specific form of lever illustrated in Figs. 1, 2 and 3 has a central or body portion 16 for pivotally mounting at the end of the bridge, and one end of the lever is bent 95 to form a finger grip 17. The opposite end of the lever has a circular portion 18 constituting a leaf, and integral with this leaf at one side thereof is a second leaf 19 connected by a short intermediate portion 20, 100 and at another side is a third leaf 21 connected by a slightly longer intermediate portion 22. In forming the lever from the blank, the leaf 18 is bent so as to lie substantially at right angles to the general direction of the length of the lever, and the leaf 19 is bent so as to lie closely and firmly in engagement with one surface of this leaf 18. The leaf 21 is bent so as to lie parallel to the leaf 18, but spaced a short distance there- 110

from to leave a socket of a width approximately equal to the width of one of the leaves. The intermediate portion 22 holds the two leaves 18 and 21 substantially rigid 5 in respect to each other, and in this intermediate portion I may, if desired, provide an aperture 23, a function of which will be set forth more fully hereinafter. In connection with this lever, I preferably employ the 10 clip substantially as shown in Figs. 6 and 7. This clip is formed from a piece of sheet metal, and has a main or body portion 24 of any desired form for proper engagement with the side of the bridge of the nose. The 15 body has an arm preferably integral therewith and connected to the lower front edge of the body. By the front edge, I mean the edge which is in front when the eyeglasses are in place on the wearer. The arm has a 20 portion 25 which is folded back to lie substantially parallel to the rear face of the body and extends substantially diagonal and upward across the rear face of the body. From the upper end of this diagonal portion 25 is an upwardly extending portion 26 also 25 lying in a plane substantially parallel to the plane of the body and terminating preferably at a short distance above the center of the body. At the upper end of this upwardly extending portion, the arm is bent outwardly to form a substantially horizontal portion 27 extending outwardly in a plane substantially at right angles to the general plane of the body. At the front edge of this 30 horizontal portion 27, there is a very short extension 28 toward the outer end of the horizontal portion, and from this extension 28 there is a depending portion 29. This depending portion constitutes what may be 35 called a leaf, and is adapted for insertion between the leaves 18 and 21 of the lever. The four leaves 18, 19, 29 and 21 are perforated to receive a pivot, and this pivot is 40 preferably in the form of a screw 30 having threaded engagement in the two leaves 18 and 19. These two leaves lie closely adjacent to each other, so that the leaf 19 may 45 be considered as constituting a lock nut for preventing the screw 30 from working loose. The leaf 29 is illustrated as having 50 an upwardly extending lug or projection 31, which may enter the opening 23 so as to prevent rotation of the leaf 29 in respect to the other two leaves. Preferably the lug is 55 somewhat narrower than the opening 23, so that a limited rotation is permitted. The extent of this rotation may be readily controlled by varying the width of the lug 31.

By forming the clip as illustrated in Figs. 60 6 and 7, the body of the clip may be moved directly toward the righthand side of the position shown in Fig. 7 by slightly bending the clip at the intersection of the portions 26 and 27 and at the intersection of the 65 diagonal portion 25 and the body. The

body of the clip may be readily bent toward or from the plane of the lens by bending the metal at the lower end of the portion 25, and it may be tilted in its own plane by bending at the intersection of the portions 28 and 29. The plane of the clip may also be varied by bending at the intersection of the portions 26 and 27. By forming the arm of the clip as above described, it is evident that the body may be supported in a plurality of different positions in respect to the lever, and, with the adjustment from one position to another, may be readily secured by grasping the parts with a pair of small pincers and bending them in the desired direction and to the desired extent. 70 75 80

Instead of forming a plurality of leaves on the lever as shown in Fig. 2, I may form them upon the clip as illustrated in Figs. 4 and 5 or as illustrated in Fig. 10. In Fig. 4, the body 24^a of the clip has two arms 26^a and 26^b, one of which terminates in a leaf 21^a and the other of which has two leaves 18^a and 19^a. The two leaves 18^a and 21^a are spaced apart to receive a leaf 29^a integral 90 with the lever. 95

In the form shown in Fig. 10, I provide the clip with a body portion 24^c and an arm having the diagonal portion 25^c and the upright portion 26^c. To the upper end of this upright portion are three leaves 18^c, 19^c and 21^c. In this case, the leaves 18^c and 21^c are spaced apart to receive a leaf of the lever. Preferably the upright portion 26^c has a slot therein between the two leaves 18^c and 21^c, to receive a lug on the lever and limit 100 or prevent the rotation of the clip. 105

In adapting my improved clip to eyeglasses of that type in which there are no levers but in which the bow or bridge is formed of spring metal, I may employ the construction shown in Figs. 8 and 9. In this form, the clip has a body portion 24^d and an arm having a diagonal portion 25^d extending upwardly and across the rear surface of the body from the lower front edge of the latter. This diagonal portion carries an upwardly extending portion 26^d lying along the rear surface of the body and extending lengthwise thereof, and from the upper end of this portion there is an offset 27^d terminating in a leaf 29^d. The leaf may be directly connected to a stud 32 carried by the lens mount 33. A screw 34 which secures the leaf in place may also secure in 110 place the end of the spring bow 35. This clip is capable of many of the same adjustments as the clip shown in Figs. 6 and 7. 115

Having thus described my invention what I claim as new and desire to secure by Letters Patent, is:

1. A mounting for eyeglasses including a clip having a body portion and an arm extending diagonally and upwardly adjacent to the back surface of the body from the 120 125 130

lower portion of said body, thence extending upwardly along said back surface, thence outwardly substantially at right angles to said body, and having a terminal portion in a plane, substantially at right angles to the plane of the last-mentioned portion, and means secured to said terminal portion for supporting said clip.

2. A mounting for eyeglasses including a clip having a body portion and an arm adjacent to the back surface of the body and extending upwardly and rearwardly from the lower front edge of said body, and thence extending upwardly along said back surface and offset at its upper end, and means secured to said offset upper end for supporting said clip.

3. A mounting for eyeglasses including a clip having a body portion and an arm integral therewith at the lower front edge thereof and folded back to lie adjacent to the back surface of said body and extending upwardly along said surface and terminating in an offset upper end, and means secured to said upper end for supporting said clip.

4. A mounting for eyeglasses including a clip having a body portion and an arm extending upwardly along the back surface of said body from the lower portion thereof, the upper portion of said arm being bent outwardly in a plane substantially at right angles to the general plane of said body portion, and provided with a terminal portion at an angle to said outwardly extending portion, and means secured to said terminal portion for supporting said clip.

5. A mounting for eyeglasses including a clip having a body portion and an arm extending diagonally upward and rearward from the lower front edge of said body, adjacent to the back surface of said body, and having a portion extending outwardly, substantially at right angles to the general plane of said body, and a terminal portion at an angle to said last-mentioned portion, and means secured to said terminal portion for supporting the clip.

6. A mounting for eyeglasses including a clip having a body portion and an arm having a body portion extending outwardly, substantially at right angles to the general plane of the body, and a terminal portion substantially at right angles to the last-mentioned portion, and means secured to said terminal portion for supporting the clip.

7. A mounting for eyeglasses having pivoted levers, each having an extension folded back to lie closely adjacent to one surface of a portion of the lever, and having a second extension folded back adjacent to the opposite surface of said portion but spaced therefrom, the clip having an arm extending between said portion and said last-mentioned

extension, a screw extending through said arm and said lever portion and through both of said extensions, having threaded engagement with said first-mentioned extension, and means at one edge of said arm for engaging with said lever to limit the rotation of the arm about said screw as a pivot.

8. A mounting for eyeglasses having a pivoted lever having an extension folded back to lie closely adjacent to one surface of a portion of the lever, a clip having an arm disposed adjacent to the opposite surface of said portion and a screw extending through said arm and said lever portion, and having threaded engagement with said extension.

9. A mounting for eyeglasses having pivoted levers each having an extension folded back to lie closely adjacent to one surface of a portion of the lever, and having a second extension folded back to lie adjacent to the opposite surface of said portion but spaced therefrom, a clip having an arm extending between said portion and said last-mentioned extension, and a pivot extending through said arm, said lever portion and both of said extensions.

10. A mounting for eyeglasses having pivoted levers each having a substantially U-shaped socket at the outer end thereof, and an extension folded back to lie adjacent to the outer surface of one wall of said socket, a clip having an arm extending into said socket and a screw extending through the walls of said socket and through said arm, and having threaded engagement with said extension.

11. A mounting for eyeglasses having a supporting member having an arm portion, a clip having an arm portion, one of said arm portions having two substantially parallel leaves and an extension folded back into engagement with the outer surface of one of said leaves, the other of said arm portions having a leaf disposed between the said leaves of the other arm portion.

12. A mounting for eyeglasses having a pivoted lever having an arm portion, a clip having an arm portion disposed adjacent one surface of an arm portion of the lever, and one of said arm portions having an extension folded back upon itself, and a screw extending through both of said arm portions and having threaded engagement within said extension.

13. A mounting for eyeglasses including a clip having a body portion and an arm disposed in a plane substantially parallel to the back surface of the body and extending diagonally upward and rearward from the lower forward edge of said body and thence extending upwardly along said back surface and means secured to said upper end for supporting said clip.

14. A mounting for eyeglasses having nose clips, each having an arm including a part

extending diagonally across the back surface of said clip from the forward edge thereof and a second part extending longitudinally along said clip and angularly relative to said first-mentioned part, and a pivoted lever secured to said arm for supporting the clip.

In testimony whereof I have signed my name to this specification in the presence of two subscribing witnesses.

JOSEPH FRIEDLANDER.
